GALLEY PUMP

Eugene L. Kilbourn, Marshall, and James M. Barker, Battle Creek, Mich., assignors to H & H Engineering Division, Barker Manufacturing Co., Battle Creek, Mich., a corporation of Michigan

Filed Dec. 8, 1966, Ser. No. 4,970

Term of patent 14 years

(Cl. D65—1)

FIG. 1 is a front and side, perspective view of a galley pump in accord with our design,

FIG. 2 is a right side, elevational view, the left side being similar thereto,

FIG. 3 is a front elevational view,

FIG. 4 is a rear elevational view, and

FIG. 5 is a plan view of the design of our invention.

The portions shown in broken lines are included for illustrative purposes only.

We claim:

The ornamental design of a galley pump, substantially as shown and described.
